UNITED STATES PATENT OFFICE.

FRED RICHMOND, OF OILFIELDS, CALIFORNIA.

OIL-WELL CONSTRUCTION.

Application filed December 15, 1924. Serial No. 755,953.

To all whom it may concern:

Be it known that I, FRED RICHMOND, a citizen of the United States, residing at Oil-fields, in the county of Fresno and State 5 of California, have invented certain new and useful Improvements in Oil-Well Constructions, of which the following is a specification, reference being had therein to the accompanying drawings.

10 This invention relates to an improvement in well constructions and it has for its object to provide a means to render it possible to add a section of pipe, from time to time, to the inner pipe in a well that is 15 being drilled in gaseous formations, without stopping the flow or circulation of the well.

The method heretofore employed to accomplish the result stated has been to pump 20 in mud of sufficient density to entirely stop the circulation of the well, causing it to be dead or quiet at the surface. This being accomplished the stuffing box casing head was taken apart and the packing taken out 25 to allow for the passage of the coupling of the joint to be put in. After the coupling was lowered the necessary distance the stuffing box casing head was replaced and circulation started again by pumping mud into 30 the inside pipe and venting it on the outside below the stuffing box casing head. This procedure is slow, sometimes requiring many tons of mud and several days' time to kill the well. Furthermore, such procedure is 35 very expensive.

In addition there is constant danger under the method stated that sufficient gas pressure will accumulate at the bottom of the hole 40 to force all of the mud out and cause damage to the hole by getting out of control and blowing out.

Furthermore there is a very evident danger of the pipe becoming "frozen" or immovable when the circulation is stopped 45 due to the fact that mud and other formations in the well, have a tendency to collect around the pipe and especially the coupling of the pipe, when the motion of the gases is stopped. By my invention, hereinafter 50 illustrated and described, I am able to avoid the necessity of stopping the circulation of the well but, upon the contrary am able to add joints of pipe at will without the necessity of pumping in any mud or interfering in any way with the circulation of 55 the well.

Further objects and advantages of the invention will be set forth in the detailed description which follows:

In the accompanying drawing:

Figure 1 is a view partly in side elevation and partly in section of apparatus constructed in accordance with the invention, and

Figure 2 is a horizontal sectional view upon line 2—2 of Figure 1.

Like numerals designate corresponding parts in both of the figures of the drawing.

In the drawing 5 designates the usual fixed casing and 6 the inner tubing which must be added to from time to time and passed down into the well and inside of the casing 5, as the drilling progresses. In 70 known apparatus of this character, a stuffing box is usually provided upon the top of the 75 casing 5 which forms a tight joint about the tubing 6. However since it is not possible to get the pipe couplings through the stuffing box or packing head with the several 80 parts in place, it has been necessary, heretofore, to remove the packing and gland for the passage of the coupling. This has required stoppage of the circulation in the well as before stated.

There is, upon the market at this time, 85 a device known as a blow out preventer, one of which is illustrated at 7 and which comprises complementary semi-circular elements adapted to be closed around the tubing 6, see Figure 2, in such manner as to prevent passage of gas or other fluid 90 through the space between the casing 5 and the tubing 6. I utilize one of the blow out preventers aforesaid in conjunction with a short sectional pipe or nipple 8 which extends upwardly from the top of the blow 95 out preventer and has the usual stuffing box 10 upon its upper end. A by pass pipe 10 establishes communication between the nipple 8 and that portion of the blow out preventer below the point of cut off of said blow 100 out preventer. A valve 11 is disposed in the pipe 10 and a relief valve 12 is adapted to discharge from the pipe 10 to the atmosphere as hereinafter set forth. The blow 105 out preventer 7 comprises the casing 13 in which the heads 14 are longitudinally movable under the influence of operating hand wheels 15 in a manner common in large 110 valve constructions. The heads 14 fit snugly within the cylinder 13 and have confronting semi-circular faces 16 in which are seated

rubber or other packing rings 17, adapted to make a tight joint about the tubing 6 when the heads 14 are moved toward each other to their limit of movement.

5 The detail construction of the blow out preventer is no part of the present invention. Any suitable type of shut off means may be provided below the nipple 8. The invention resides more particularly in the 10 provision of the nipple 8 or its equivalent with the stuffing box thereon in conjunction with a shut off means therebelow, irrespective of what particular type of shut off means I may see fit to employ. The invention 15 further resides in the provision of the by pass pipe 10 for the purposes herein-after described. The operation of the device is as follows: If it be desired to add a section to the tubing 6, the heads 14 are 20 moved inwardly to form a tight joint about the tubing 6 and shut off communication of the interior of nipple 8 with the interior of the casing 5. With the valve 11 closed the valve 12 is opened to vent the interior 25 of nipple 8 to the atmosphere, thereby relieving the pressure in said nipple. 6^a designates the section of tubing to be added and 6^b the coupling by which the section 30 6^a is united with the tubing 6. The glands 9^a and 9^c respectively are removed or, alternately, the whole stuffing box may be unscrewed from the top of the nipple. Then 35 the tubing 6^a and coupling 6^b are screwed on to the tubing 6 and the whole lowered until the coupling 6^b lies within the nipple 8, after which the stuffing box, or the packing, as the case may be, is restored to its 40 original position and made to constitute a tight joint about the section 6^a. Then valve 12 is closed and valve 11 is opened to equalize the pressure in casing 5 and nipple and then the heads 14 are moved apart to restore free connection between nipple 8 and casing 5. After the heads 14 have 45 been separated the coupling 6^b may pass downwardly through the blow out preventer until the next coupling is close to the top of the stuffing box. The operation recited may be repeated as necessary. Of course 50 in pulling the tubing out of the well, the process is reversed.

The reason for keeping the blow out preventer open at all times except when sections of tubing are being added as above set forth is that this reduces wear on the packing of the blow out preventer to a minimum. This packing would last but a very short time if it were in constant contact with the

tubing. However, the presence of the blow out preventer is a safeguard since it is available at all times and can be shut off if the packing head gets out of order or the well comes in. The by pass line is of great value since it is very hard to operate the blow out preventer without equalizing the pressure in the nipple 8 and casing 5.

It is to be understood that the invention is not limited to the precise construction set forth but that it includes within its purview whatever changes fairly come within either the terms or the spirit of the appended claims.

Having described my invention, what I claim is:

1. The combination with a casing and a drill element movable therein, of a shut off device adapted to make a tight joint between the casing and the exterior of the tubing, a chamber of such size as to house a tubing coupling, located above the cut off device and a packing head carried by said casing.

2. A structure as recited in claim 1 in combination with a by-pass line extending from said chamber to a point below the cut off device.

3. A structure as recited in claim 1 in combination with a by pass line, extending from the chamber to a point below the shut off device and means for venting said chamber to the atmosphere.

4. A device of the character described comprising a casing and a drilling element therein, a shut off device comprising elements adapted to form a tight joint about the exterior of the drilling element, a fixed nipple extending upwardly from the shut off device through which the packing element moves, and a packing head upon the upper end of the nipple and a by-pass line extending from said nipple to a point below the shut off device.

5. A structure as recited in claim 4, in combination with means for venting said nipple to the atmosphere.

6. The combination with a casing and a drill element therein, of a shut off device adapted to make a tight joint between the casing and the exterior of the drill element, a chamber located above the shut off device of such amplitude as to receive a drill coupling and pressure retaining means carried by said chamber.

In testimony whereof I hereunto affix my signature.

FRED RICHMOND.
